CLAIM

The ornamental design for a sample collector with nested in vitro diagnostic device (IVD), as shown.

DESCRIPTION

FIG. 1 shows a perspective view of a sample collector with nested in vitro diagnostic device (IVD).

FIG. 2 shows a second perspective view thereof.

FIG. 3 shows a front view thereof.

FIG. 4 shows a rear view thereof.

FIG. 5 shows a top view thereof.

FIG. 6 shows a bottom plan view thereof.

FIG. 7 shows a right side view thereof.

FIG. 8 shows a left side view thereof; and,

FIG. 9 shows a perspective view with un-nested versions of the device.
